UNITED STATES PATENT OFFICE.

MOSES MOSLER, OF CINCINNATI, OHIO.

SAFE.

SPECIFICATION forming part of Letters Patent No. 239,110, dated March 22, 1881.

Application filed January 31, 1881. (No model.)

To all whom it may concern:

Be it known that I, MOSES MOSLER, of Cincinnati, in the county of Hamilton, State of Ohio, have invented certain new and useful 5 Improvements in Safes, of which the following is a specification.

This invention relates to the door and casing in safes and other secure receptacles, and especially to that class known as "fire-proof safes." Its objects are to strengthen the corners of the door and its frame, and render it more easy to make a perfectly-fitting air-tight joint between the door and jamb. These objects are attained by making the steps or 15 tongues and grooves at the corners of the door and the door-jamb to return by two obtuse angles, instead of by right angles, as heretofore, and by providing the blank spaces left at the corners of the door with plugs to enter 20 corresponding holes in the casing, or vice versa.

Figure 1 of the accompanying drawings is a front view of an open safe embodying my improvements; and Fig. 2 is a detail view, in 25 section, of the corner.

A is the frame of the safe. The sides, top, and bottom of the door-opening are formed into steps in the usual manner. All of these steps except the outer one return across the 30 corner of the safe at angles of about one hundred and thirty-five degrees, making the inner opening an eight-sided figure. The sides of the outer depression are returned at right angles to receive the rectangular front of the door. The triangular spaces left at each corner of the door-jamb have triangular depressions *a* to receive the correspondingly-shaped pins *b*, which project from the inner surface 35 of the corners of the door B. The pins are ta-

pering or curved to permit the door to swing 40 into the frame and open without locking.

In case of fire, the danger to the contents of the safe arise principally from the injury the safe receives in falling upon one of its corners when the floors or walls of the building 45 give way. The injury usually occurs at the corners of the door-frame, owing to the acute angle of the door cutting or wedging into the jamb.

My improved safe is as little liable to injury 50 by falling upon the corner as it is were it to fall upon any of the sides, as the corners are much stronger, and more room is left for the filling without lessening the capacity of the safe.

I claim—

1. In a safe, the combination, substantially as before set forth, of the stepped door-frame, the extreme interior opening of which is rectangular, while the sides of the steps are diagonally joined and the stepped door fitting such door-frame.

2. In a safe, the combination, substantially as before set forth, of the stepped door-frame, the two extremes of the opening of which are 65 rectangular, while the sides of each intervening step are diagonally joined, the stepped door fitting such door-frame, and inwardly-projecting dowel-pins in the enlarged corner spaces of the outer ledge of the door, adapted 70 to enter dowel-holes in the corresponding enlarged corner spaces of the door-frame step, against which such door-ledge shuts.

MOSES MOSLER.
